UNITED STATES PATENT OFFICE.

HUGH B. FULTZ, OF WESTON, WEST VIRGINIA, ASSIGNOR OF ONE-HALF TO WILLIAM D. NEWLON, OF CLARKSBURG, WEST VIRGINIA.

TRAVELING-BAG LOCK.

1,359,982.

Specification of Letters Patent. Patented Nov. 23, 1920.

Application filed March 25, 1920. Serial No. 368,527.

To all whom it may concern:

Be it known that I, HUGH B. FULTZ, a citizen of the United States, residing at Weston, in the county of Lewis and State of 5 West Virginia, have invented a new and useful Traveling-Bag Lock, of which the following is a specification.

This invention has reference to latch constructions, and more particularly to latch 10 constructions especially designed for securing the mouths of satchels, hand-bags and the like.

The primary object of the invention is to provide a latch having locking means designed to be unlocked only when the locking 15 levers have been moved to predetermined positions, thus preventing unauthorized persons from opening the satchel or bag to which the invention is applied.

20 A further object of the invention is to provide a latch of this character having slide- able locking rods, the rods being capable of adjustment to permit the operating position thereof to be changed.

25 With the foregoing and other objects in view which will appear as the description proceeds, the invention resides in the combination and arrangement of parts and in the details of construction hereinafter described 30 and claimed, it being understood that changes in the precise embodiment of the invention herein disclosed, may be made within the scope of what is claimed, without departing from the spirit of the invention.

35 Referring to the drawing:

Figure 1 illustrates a longitudinal sectional view through the frame of a satchel mouth, the same being supplied with a latch constructed in accordance with the present 40 invention.

Fig. 2 illustrates a sectional view taken on line 2—2 of Fig. 1.

Fig. 3 illustrates a fragmental detail view of one section of the satchel mouth frame, 45 and

Fig. 4 illustrates a sectional view taken on line 4—4 of Fig. 1.

Fig. 5 illustrates a fragmental detail view of the mouth frame.

50 Referring to the drawing in detail, the reference characters 5 and 6 respectively represent the opposed side sections of a satchel, to which sections are attached the opposed sections of the mouth frame indi-

cated by the reference characters 7 and 8 re- 55 spectively, the connections between the sections 7 and 8 and sections 5 and 6 of the satchel, being made through the rivets 9, which pass through suitable openings pro- 60 vided in the sections 7 and 8 and inner clamping plates 10.

The latch forming the important feature 65 of the present invention includes the rectangular metallic frame indicated at 11, one of the side walls of which being connected to the section 7 of the mouth frame, by means of the rivets 9, and as shown this metallic frame 11 is provided with a central opening to accommodate the thumb bar of the latch indicated at 12, the lower end of which 70 thumb bar 12 has connection with the plate 13 disposed within the metallic frame 11.

Formed adjacent the respective ends of the plate 13, are suitable openings adapted to accommodate the guide pins 14 which 75 have their ends secured to the opposed upper and lower walls of the frame 11, and provide means for supporting the coiled springs 15, the upper ends of which contact with the under surface of the plate 13, the 80 lower ends thereof having connection with the upper surface of the lower wall of the frame 11 in a manner to normally urge the plate 13 upwardly, for purposes to be hereinafter more fully described.

85 Disposed adjacent one edge of the plate 13, and extending upwardly therefrom, are the spaced lugs 16 which coöperate with the keepers 17 carried by the section 8 of the satchel mouth, and which extend laterally 90 therefrom. From the foregoing it is obvious that when the sections of the mouth frame are moved to their closed positions, the keepers 17 lie within the paths of travel of the lugs 16 to receive the same for accomplishing the locking of the satchel.

The outer surfaces of the respective lugs 16 are curved so that they will ride over the outer edge of the keepers 17, the plate 13 carrying the lugs being depressed under the 100 tension of the spring 15, whereupon the lugs 16 move to their locking positions within the keepers 17.

Formed substantially intermediate the length of the plate 13, is an opening 18 105 adapted to provide a clearance for the upwardly extending lug 19, which lug is of a size slightly less than the size of the open-

ing to permit the lug to move within the opening 18 to permit the latch proper to be operated to unlock the mouth of the satchel.

This lug 19 is carried by the section 20 of the controlling rod 21, and this section 20 operates through suitable openings provided in the end walls of the metallic frame 11 so that the rod 20 may be moved to various positions to the end that the lug 19 may be moved to a position under the opening 18.

A turn buckle connects the section 20 with the controlling rod 21, the turn buckle being indicated at 22, and it will be seen that by operating the turn buckle, the section 20 may be moved toward and away from the rod 21 to change the relation of the lug 19 with the opening 18.

The upper end of the controlling rod 21 is forked as at 23 and has connection with the locking arm 24 of the sliding actuating member 25, which actuating member 25 is provided with suitable markings on the surface thereof, which markings coöperate with certain markings provided on the mouth frame so that the actuating member 25 may be moved to a predetermined position to cause the lug 19 to be moved to a position in registry with the opening 18.

At the opposite end of the mouth frame, 30 is a similar actuating member 26 which is also provided with graduations, and this actuating member 26 is provided with a locking arm 27 which has pivotal connection with the controlling rod 28 that has connection with the rod 29 through the turn buckle 30, in a manner to permit the rods 28 and 29 to be adjusted with relation to each other to change the distance of movement of the rod 29 to accomplish the unlocking of the satchel.

Embracing the rectangular frame 11, is a frame 31 which has its free ends formed into locking pins 32, which locking pins 32 are disposed in suitable spaced relation with 45 each other to coöperate on opposite sides of the thumb bar 12.

Provided in opposed side edges of the thumb bar 12, are the openings 33 adapted to receive the locking pins 32 for locking 50 the thumb bar 12 against reciprocating movement within the mouth frame to prevent the operation of the latch. From the foregoing it will be obvious that if the actuating member 26 is moved to a position so 55 that the locking pins 32 will lie in positions in close proximity with the side edges of the thumb bar 12, the thumb bar 12 may be depressed to disengage the lugs 16 from their keepers 17, but if the actuating member 26 is moved beyond a predetermined 60 distance, in either direction, one of the pins 32 will seat in one of the openings 33 to cause the locking of the thumb bar 12 in the position as indicated by Fig. 1 of the 65 drawing.

Coöperating with each of the locking arms of the actuating members 25 and 26, are the adjustable keepers 34 which are secured to the opposed section of the mouth frame of the satchel by means of the screws 70 35, to permit the keepers 34 to be moved with relation to the locking arms 24 and 27 to change the location of the openings 36 with relation to the locking arms 24 and 27.

In the operation of the device, the turn 75 buckles 22 and 30 are adjusted to predetermined positions, so that when predetermined indications on the actuating members 25 and 26 are in registry with certain indications of the mouth frame, the locking 80 arms 24 and 27 are moved to positions in registry with the openings 36, and the locking pins 32 are in positions adjacent the side edges of the thumb bar 12. The lug 19 is now in a position in registry with the 85 opening 18, and the thumb bar 12 is free to move downwardly to disengage the lugs 16 from their keepers 17, thus permitting the mouth of the satchel to be opened.

It is of course obvious that when the 90 satchel mouth is moved to its closed position, the actuating members 25 and 26 are moved to cause one of the locking pins 32 to be positioned within one of the openings 33 of the thumb bar 12, and the lug 19 to be 95 moved to a position out of registry with the opening 18 or in the path of travel of the plate 13 to prevent the thumb bar 12 from being depressed to accomplish the unlocking of the satchel.

What is claimed as new is:—

1. In combination with the opposed sections of a mouth frame of a satchel, a latch including a frame, a plate supported within the frame, said plate carrying lugs, keepers carried by one of the sections and adapted to receive the lugs for locking the sections together, a thumb bar having connection with the plate for moving the plate within the frame, means within the frame for restricting movement of the plate, and means including locking pins adapted to coöperate with the thumb bar for restricting movement thereof.

2. In combination with the opposed sections of a mouth frame of a satchel, a latch including a metallic frame secured to one of the sections, a plate carrying locking lugs, operating in the metallic frame, actuating members, a rod having connection with the actuating members and carrying locking pins, a thumb bar for operating the plate, said thumb bar having openings adapted to receive the locking pins for locking the thumb bar against movement, and means for coöoperating with the plate for restricting movement of the thumb bar.

3. In combination with the opposed sections of a mouth frame of a satchel, a latch including a metallic frame, a plate operat-

ing within the frame, said plate carrying locking lugs, keepers carried by the opposed section and adapted to receive the locking lugs for locking the sections of the mouth frame together, means within the metallic frame for locking the plate in one position, means for moving the first mentioned means to permit of movement of the plate, a thumb bar for operating the plate, and 10 means for engaging the thumb bar to restrict movement thereof.

4. In combination with the opposed sections of a mouth frame, of a satchel, a latch including a metallic frame carried by one 15 of the sections, a plate carrying locking lugs supported within the frame, keepers carried by the opposed section and adapted to receive the locking lugs, means for normally urging the locking lugs to positions within 20 the keepers, a thumb bar having connection with the plate for moving the plate in one direction, means coöperating with the plate for restricting movement thereof, and means coöperating with the thumb bar for further 25 restricting movement of the plate.

5. In combination with the opposed sections of a mouth frame of a satchel, a latch including a metallic frame carried by one of the sections, means carried by the frame for supporting locking lugs, keepers carried by the opposed section and adapted to coöperate with the locking lugs for securing the sections together, actuating members carried by one of the sections, adjustable slotted keepers carried by the opposed section, each of the actuating members including a locking arm adapted to operate in the slotted keepers, for securing the sections together adjacent the ends thereof, a thumb bar for operating the first mentioned 35 means, and means controlled by the actuating members for restricting movement of the thumb bar.

In testimony that I claim the foregoing as my own, I have hereto affixed my signature in the presence of two witnesses.

HUGH B. FULTZ.
